UNITED STATES PATENT OFFICE.

CHARLES A. CLARK, OF HARTFORD, CONNECTICUT.

ELECTRIC SWITCH.

No. 899,205.

Specification of Letters Patent. Patented Sept. 22, 1908.

Application filed May 24, 1907. Serial No. 375,445.

To all whom it may concern:

Be it known that I, CHARLES A. CLARK, a citizen of the United States, and a resident of Hartford, in the county of Hartford and State of Connecticut, have invented a new and Improved Electric Switch, of which the following is a specification.

My invention relates more especially to that class of switches in which the operating parts are actuated as by means of a push button to make and break a circuit, and the object of my invention is to provide a device of this class extremely simple and cheap in construction and operation but more especially one that shall be extremely effective in making and breaking the circuit; one in which the action of the parts shall be extremely quick.

A form of device in the use of which these objects may be attained is illustrated in the accompanying drawings, in which—

Figure 1 is a side view of a device embodying my invention with the parts in position occupied when the circuit is broken, the inner closing casing not being shown. Fig. 2 is a detail view in section through the device showing the relative position of the plate and switch bar with the parts located as in Fig. 1. Fig. 3 is a view similar to Fig. 1 but with the parts in position just before movement of the trip plate and switch bar. Fig. 4 is a view similar to Fig. 3 but with the parts in position just after the movement of the trip plate, and with the push button at the inner limit of its movement. Fig. 5 is a view in section through the device showing the relative position of the trip plate and switch bar with the parts placed as in Fig. 4. Fig. 6 is a detail view in cross-section 40 through the device on the line indicated in Fig. 3.

In the accompanying drawings the numeral 8 denotes a base, of insulating material, which may be a part of a casing of porcelain or other insulating material inclosing the mechanism, or may be a part separately formed from said casing. Posts 9 extend from the base on the outer end of which is supported a face plate 10. Conductors 11 are secured to the base, these conductors having wire attaching means 12. The conductors are electrically connected with the blade contacts 13. A support 14 is secured

to the base 8, and is of proper length and form to receive and support the moving parts of the mechanism. A shaft or spindle 15 is rotatably mounted in the support, and a switch bar 16 having blades or contacts 17 is secured to the shaft. A trip plate 18 is also secured to the shaft, the parts being properly insulated in a manner well-known in devices of this class as by the insulating pieces 19 or otherwise. In the preferred form of construction a clamp plate 20 is secured to the shaft and has ears 21 projecting and engaging recesses in the side of the trip plate 18, as plainly shown in Figs. 2 and 5 of the drawings. The trip plate has an arm 22 projecting through a slot 23 in the support 14 in position to receive the thrust of one end of the spring to be hereinafter described. This trip plate also bears a trip 24.

An actuating lever 25 forming primary means for operating the parts is loosely mounted on the shaft 15, and this lever is pivotally engaged at opposite ends with the shanks 26 of push buttons or actuators 27—28 suitably mounted in the face plate 10. The actuating lever 25 has a detent holder 29 and a detent actuator 30. The holder is preferably a slight projection with its edge curved to fit a curved surface 31 on the edge of the detent plate 32. The detent actuator is preferably a shoulder on the lever arranged to engage the edge of the detent plate to move the latter. The lever 25 also has a tensioning arm 33 for the spring 34 mounted on the shaft 15. The detent plate 32 is pivotally mounted on a stud 36 secured to the support 14 and has detents 37—39 projecting through slots 38 in the support 14 in position to engage the trip 24 upon the trip plate 18.

This construction provides a switch in which there is a minimum amount of wear of the parts and a consequent positive operation for a maximum length of time. It provides a device in which a sharp and decisive release and action of the parts is obtained.

The operation of the device is as follows: The parts being in the position shown in Fig. 1 with the push button 27 extended, the latter is pushed inward rocking the lever 25 on its pivot and carrying the spring tensioning arm 33 to the right, or to the position shown in Fig. 3, thus placing the spring under tension,

the parts now being in the position shown in Fig. 3. During this movement the engagement of the holder 29 with the recess 31 in the detent plate has prevented movement of the detent while permitting movement of the lever, the curve of the edge of the holder 29 and of the recess 31 being struck from the same center. The switch bar is prevented from movement during this operation by reason of the engagement of the trip 24 with the detent 37, as shown in Fig. 2. The push button 27 passing beyond the position shown in Fig. 3 and to that shown in Fig. 4 carries the lever 25 to such point that the shoulder 30 engaging the edge of the detent plate 32 swings it on its pivot, moving the detent 37 out of the path of the trip 24 to the position shown in Fig. 5, allowing the trip plate to move to the position shown in Fig. 5 under the impulse of the spring 34.

It will be noted, by referring to Fig. 4, that in this position of the parts the spring is now exerting pressure upon the tensioning arm 33 but in a direction contrary to that in which the lever was moved to cause the parts to assume this position. Pressure upon the push button 27 now being relieved the latter moves backward to the position shown in Fig. 3 when the detents assume the position shown in Fig. 2, but with the trip plate in the opposite position, and with the switch blade in engagement with the contacts. A reversal of the above described operation will disengage the switch blade from its contacts.

What I claim as my invention and desire to secure by Letters Patent is:—

1. A switch bar with its contacts and connections, a trip operatively connected therewith, means for moving the trip, a detent to engage the trip but arranged for disengagement therefrom, means for positively holding the detent against movement during initial movement of the actuator but permitting quick release and movement of the detent at final movement of the actuator, and an actuator for positively moving the detent from the path of movement of the trip.

2. A switch bar with its contacts and connections, a trip operatively connected with the bar, means for operating the trip, a pivoted operating lever having a holder with a holding surface formed on the arc of a circle struck from its pivot, a swinging detent plate operatively connected with the trip and having a recess formed to fit said holding surface, and means for operating said detent plate.

3. A switch bar with its contacts and connections, a trip plate operatively connected with the bar and bearing a trip, a spring for actuating the trip plate, means for tensioning the spring, detents located in the path of movement of said trip but arranged for disengagement therefrom, means for posi-

tively holding the detents against movement during initial movement of an actuator but permitting quick release and movement of the detent during final movement of said actuator, and the actuator for positively moving said detents out of the path of movement of the trip.

4. A base with a support extending therefrom, a switch bar, and a trip plate operatively connected therewith and mounted on one side of the support, contacts and connections for said switch bar, an operating lever and a detent plate pivoted to the support on the side opposite the trip plate said plate having detents projecting through the support to engage a trip on the trip plate, means for holding the detent plate against movement in an initial operation of the parts, and means for moving the detent plate to disengage the detents from said trip in a subsequent operation of the parts.

5. A base having a support extending therefrom, a switch bar and a switch plate operatively connected therewith and both mounted on one side of the support, connections and contacts for said switch bar, a spring arm extending from the trip plate through the support, a lever located on the opposite side of the support from the trip and having a spring engaging arm, means for operating the lever, a detent mounted on the same side of the support with said lever and having detents extending through the support to engage a trip on the trip plate, means for holding the detent plate against movement in an initial position of the device, and means for moving the detent plate to disengage the detents from the trip in a subsequent operation of the parts.

6. A switch bar with its contacts and connections, a trip plate operatively connected with the bar and having a trip, means for forcing the trip plate to move said bar, an operating lever having a holder, a swinging detent plate having detents to engage said trip and arranged for engagement with and disengagement from said holder, and means for operating the detent plate to move the detents out of the path of said trip.

7. A switch bar with its connections and contacts, a trip plate operatively connected with the switch bar and having a trip, a spring for operating the trip plate, an operating lever to operate said spring, said lever having a curved shaped holder, a pivotally mounted detent plate with a curved surface fitting said holder and with detents to engage said trip, said lever and detent plate being arranged for engagement and disengagement and means for moving the plate to disengage the detents from said trip.

8. A base with a support extending therefrom, a switch bar mounted on the support, contacts and connections for said bar, a trip plate operatively connected with the bar and

having a trip, a lever for operating the parts, a spring with one end in engagement with the trip plate and the other with said lever, a holder projecting from the operating lever a detent plate arranged for engagement with and disengagement from said holder and having detents to engage said trip, and

means for moving said holder to disengage the detents from said trip.
